PLACE MAT OR THE LIKE

John E. Stengel, Bon Air, Va., assignor to Reynolds Metals Company, Richmond, Va., a corporation of Delaware

Filed July 16, 1965, Ser. No. 86,175

Term of patent 14 years

(Cl. D92—26)

I claim:

The ornamental design for a place mat or the like, as shown and described.
